(57) **CLAIM**

The ornamental design for a pallet, as shown and described.

DESCRIPTION

FIG. 1 is a perspective view of the pallet showing my new design;

FIG. 2 is a top plan view thereof;

FIG. 3 is a bottom plan view thereof;

FIG. 4 is a front elevational view thereof, the rear elevational view being a mirror image thereof; and,

FIG. 5 is a left side elevational view thereof, the right side being a mirror image thereof.

The broken lines shown are for environmental purposes only and are not part of the claimed design.
